UNITED STATES PATENT OFFICE.

CARL F. LAUBER, OF PHILADELPHIA, PENNSYLVANIA.

FUMIGATOR.

SPECIFICATION forming part of Letters Patent No. 577,867, dated March 2, 1897.

Application filed May 22, 1896. Serial No. 592,671. (No model.)

To all whom it may concern:

Be it known that I, CARL F. LAUBER, a citizen of the United States, residing at Philadelphia, in the county of Philadelphia and 5 State of Pennsylvania, have invented certain new and useful Improvements in Fumigators, of which the following is a specification.

My invention relates to a new and useful improvement in fumigators, and has for its 10 object to provide a device of this description which will be simple in construction and cheap of manufacture and by means of which insect life may be exterminated from plants.

With these ends in view my invention consists in the details of construction and combination of elements hereinafter set forth, and then specifically designated by the claim.

In order that those skilled in the art to which this invention appertains may understand 20 how to make and use the same, I will describe its construction and operation in detail, referring to the accompanying drawings, forming a part of this specification, in which—

Figure 1 is a side view of my improved fumigator; Fig. 2, a central section thereof, and Fig. 3 a section at the line *x x* of Fig. 2.

In carrying out my invention I provide a cylindrical receptacle A of sufficient size to hold the desired quantity of tobacco or other 30 fumigating material, and the open end of this cylinder is closed by a cap B, having a number of perforations C formed therein to permit the indrawing of the air and the expelling of the smoke, as hereinafter set forth. The 35 opposite end of the cylinder is permanently closed by a circular plug D, having a flange E of a size adapted to fit within said cylinder, and upon this annular flange rests the screen F, which latter is preferably of wire- 40 gauze or made of any suitable material. By this arrangement when tobacco is placed in the receptacle, as shown in Fig. 2, it rests upon the screen, thus leaving a space G unoccupied. Upon the lower end of the plug 45 is formed a nipple H, by means of which the rubber bulb I is attached to said plug, the bead J serving to prevent the accidental withdrawal of said bulb, as will be readily understood.

50 The operation of my improvement is as fol-

lows: Tobacco is placed within the receptacle, and after being lighted the receptacle is closed by the cover B and the air in the bulb expelled through the receptacle by the pressure of the hand and a fresh quantity of air drawn 55 through said receptacle in the opposite direction by the releasing of the bulb, which will assume its normal shape by the elasticity of the material of which it is composed. This indrawing of the air will supply the necessary oxygen to the burning tobacco to continue the smoldering combustion after the manner of pipe-smoking, and when the air is again excluded from the bulb the smoke which has been drawn into said bulb will be forced 60 through the perforations and driven to a considerable distance, and when directed toward the plants to be fumigated will completely envelop said plants, permeating every part thereof and, as is well known, exterminating 65 the insect life which may exist thereon. The upper surface of the cover B is somewhat convexed, the object of which is to cause the smoke issuing from the perforations to diverge 70 in either passage from the apparatus, thus 75 causing attenuation of said smoke and permitting it to envelop a larger number of plants.

One of the principal advantages of my improvement is that the device may be held in the hand and manipulated with little or no 80 effort on the part of the operator, the screen F serving to prevent the clogging of the passage K by nicotine or the downfalling of the tobacco, and the shape of the plug D preventing a sufficient amount of heat from reaching 85 the bulb to affect the same.

When it is necessary to clean the apparatus, it is easily accomplished by removing the cover B, which gives access to the cylinder, and also the bulb I, which gives access to the 90 opening K, it being understood that the screen F is also removable.

Having thus fully described my invention, what I claim as new and useful is—

In a device of the character described a cylinder, a cover on one end, said cover having a convex surface with perforations therethrough, a bead formed on said cylinder to limit the position of the cover, a plug secured 95 in the other end by a flange, a wire-gauze rest- 100

ing on said flange leaving an air-space between the gauze and the plug, a nipple formed with said plug ending in a head, said plug having a passage therethrough and an elastic 5 bulb attached to the nipple as and for the purpose described.

In testimony whereof I have hereunto af-

fixed my signature in the presence of two subscribing witnesses.

CARL F. LAUBER.
